Des. 233,480
Patented Oct. 29, 1974

233,480

EYEGLASS FRAME FRONT

Howell Stevens Jobbins, Jr., Warwick, R.I., assignor to
Universal Optical Company, Inc., Providence, R.I.

Filed Mar. 12, 1973, Ser. No. 340,075

Term of patent 14 years

Int. Cl. D16—06

U.S. Cl. D57—1 F

FIG. 1 is a front elevational view of an eyeglass frame front embodying my new design;

FIG. 2 is a top plan view thereof;

FIG. 3 is a side elevational view thereof.

I claim:

The ornamental design for an eyeglass frame front, substantially as shown.
